CLAIM

The ornamental design for a cake pan, as shown and described.

DESCRIPTION

FIG. 1 is a perspective view of the cake pan;

FIG. 2 is a front elevational view of the cake pan;

FIG. 3 is a rear elevational view of the cake pan;

FIG. 4 is a left side elevational view of the cake pan;

FIG. 5 is a right side elevational view of the cake pan;

FIG. 6 is a top plan view of the cake pan; and,

FIG. 7 is a bottom plan view of the cake pan.

The subject matter shown in dashed lines, and any surfaces of the design not shown, including interior surfaces, form no part of the claimed invention.
